UNITED STATES PATENT OFFICE.

CHARLES B. MORROW, OF CHICAGO, ILLINOIS, ASSIGNOR TO THE GREAT WESTERN FIXTURE WORKS, OF SAME PLACE.

DESIGN FOR A DISPLAY-RACK.

SPECIFICATION forming part of Design No. 28,772, dated May 31, 1898.

Application filed April 11, 1898. Serial No. 677,237. Term of patent 7 years.

To all whom it may concern:

Be it known that I, CHARLES B. MORROW, a citizen of the United States, residing at Chicago, in the county of Cook and State of Illinois, have invented and produced a new and original Design for Display-Racks, of which the following is a clear and exact description, such as will enable others skilled in the art to which it appertains to make and use the same.

My design relates to display-racks.

The drawing represents a perspective view of my new design for display-racks.

The leading feature of my design consists of a series of vertical standards having step-like inclined bars secured thereto and a series of horizontal rods carried thereon.

1 represents a series of rear standards.

2 represents a series of front standards, which are shorter than the rear standards.

3 represents a series of step-like side supports secured to the front and rear standards.

4 are a series of secondary standards secured to the supports 3 and projecting upwardly therefrom.

5 are a second and upper series of step-like inclined supports, the lower ends of which are secured to the standards 4 and the upper rear ends to the standards 1.

6 are a series of horizontal bars carried in 30 seats upon the supports 3 and the supports 5 and serve to hold the goods displayed.

Standards 4 have a pivotal connection 7 upon the supports 3, and 8 are adjustable connections between the series of supports 3 35 and 5 and the standards 1, 2, and 4.

9 are bed-plates for the standards.

Having described my invention, what I claim as new, and desire to secure by Letters Patent, is—

The design for a display-rack, substantially as shown and described.

In testimony whereof I affix my signature in the presence of two witnesses.

CHARLES B. MORROW.
